G. C. Kennedy,
Attorney.

UNITED STATES PATENT OFFICE.

NORMAN A. LICHTY, OF WATERLOO, IOWA, ASSIGNOR TO LICHTY METAL PRODUCTS COMPANY, OF WATERLOO, IOWA, A CORPORATION OF IOWA.

SKYLIGHT-WINDOW FRAMING.

1,325,794.

Specification of Letters Patent. Patented Dec. 23, 1919.

Application filed March 3, 1919. Serial No. 280,329.

To all whom it may concern:

Be it known that I, NORMAN A. LICHTY, a citizen of the United States of America, and a resident of Waterloo, Blackhawk 5 county, Iowa, have invented certain new and useful Improvements in Skylight-Window Framings, of which the following is a specification.

My invention relates to improvements in 10 sky-light window-framing, and the object of my improvement is to provide a sky-light window-framing with lateral plate extensions adapted to extend under and support roof shingles, said plate extensions being 15 formed with means for properly supporting the shingles while deflecting moisture or rain therefrom.

This object I have accomplished by the means which are hereinafter described and 20 claimed, and which are illustrated in the accompanying drawings, in which Figure 1 is a front elevation of a sky-light window and its special framing of my invention as applied to an inclined shingle roof structure, and Fig. 2 is an enlarged cross-section of a lateral or side portion of said window framing.

Similar numerals and characters of reference denote corresponding parts throughout the several views.

My improved window framing B consists of a metal plate A having one or more relatively large openings to be covered by glazing 8. This plate A is to be mounted in a 35 well-known manner over a suitable opening in the sheathing 15 of the inclined roof of a hog-house or other building. The plate A may be an integral one, or constructed of spaced horizontal strips 10 and 12 connected at their ends to the ends of side-strips 1 by soldering or other means. These side-strips 1 are formed or rolled with inclined ribs, crimps or corrugations 2, spaced apart and raised from the upper surface of 45 the plate. Shingles 14 are laid in the usual overlapping relation upon the side-strip 1 and supported upon the raised ribs 2 thereon.

Any desired engaging or securing means 50 may be adopted for supporting and sealing the glass-plates 8 over the openings in said window-framing. I have shown a specific mounting for glazing.

Referring to said Fig. 2, the inner longitudinal edge-part of each side-strip 1 is bent

upwardly at a right angle at 3, thence downwardly at 4 parallel to the part 3, thence at a right angle at 5, and thence again at a right angle at 6. The glass-plate 8 rests upon the upper edge of the part 6, spaced 60 from the part 5, and with its edge abutting upon the part 4. The parts 4, 5 and 6, while supporting the plate 8, also provide a channel for water. The numeral 7 denotes an angularly bent strip placed astride the fold 65 of the parts 3 and 4 and detachably secured thereto by clips 9, the clips being soldered to the part 4, passed through slots not shown in the strip 7 and bent upon the latter. Sealing-strips 11 extend over the upper 70 edges of the plates 8, as also other sealing-strips 13 extend over the lower edges of the plates from the strips 10 and 12 respectively. The strips 7, 11 and 13 cover the joints between the glazing and the supports therefor. 75

The ribs or crimps 2 on the side-strips 1, are preferably inclined from the outer edges of the strips downwardly toward the adjacent side-parts 3 of the window-framing B, to deliver moisture away from the 80 overlying shingles 14, the ribs being of such an inclination and so spaced as to extend past each other and prevent passage of water or moisture.

The dotted lines in said Fig. 1 show the 85 arrangement of said ribs under the overlying shingles, whereby the shingles are each supported on at least two ribs, and as the ribs are positioned obliquely to the shingles, the grain of the latter is so crossed as not 90 to be liable to split immediately over the ribs as might be the case were the ribs positioned parallel with the grain or longitudinal with the shingles.

Having described my invention, what I 95 claim as new, and desire to secure by Letters Patent, is:

1. A sky-light window-framing, comprising a plate having an opening and provided with engaging-means for glazing about said 100 opening, portions of the plate being crimped obliquely.

2. A sky-light window-framing, comprising a plate having an opening and provided with engaging-means for mounting glazing 105 along its inner marginal border, the end portions of said plate having spaced parallel crimps extending from its outer margin toward the engaging means.

3. A sky-light window-framing, comprising 110

ing a plate having an opening and provided with a raised rim about the opening, said plate having on its opposite end portions parallel raised parts arranged obliquely toward the adjacent parts of said rim.

4. The combination with sky-light window-framing, of a plate bordering there-

upon, said plate being formed at its ends with raised spacing projections inclined from without downwardly toward the opening in said framing.

Signed at Waterloo, Iowa, this 13th day of Feb. 1919.

NORMAN A. LICHTY.
